CHARLES L. PEIRCE, JR., OF PITTSBURGH, PENNSYLVANIA, ASSIGNOR OF ONE-HALF TO HUBBARD & CO., OF PITTSBURGH, PENNSYLVANIA, A CORPORATION OF PENNSYLVANIA.

SEPARABLE INSULATOR-THIMBLE STRUCTURE.

1,219,862.

Specification of Letters Patent. Patented Mar. 20, 1917.

Application filed May 17, 1916. Serial No. 98,032.

To all whom it may concern:

Be it known that I, CHARLES L. PEIRCE, Jr., a citizen of the United States, and a resident of Pittsburgh, in the county of Allegheny and State of Pennsylvania, have invented certain new and useful Improvements in Separable Insulator-Thimble Structures, of which the following is a specification.

10 My invention relates to separable thimble supports for the larger type of insulators intended for service in high voltage transmission systems.

15 Insulators for high voltage service are large and usually of porcelain, and owing to the differences in shrinkage in different lots of clay it is practically impossible to produce such porcelain insulators with accurately threaded bores, and the insulators 20 cannot therefore be screwed directly onto unyielding pins or thimbles without breaking or straining them. It has therefore been the usual practice to cement thimbles into the insulators, the thimbles being 25 threaded on their inner sides to accurately and snugly fit supporting pins and having also threads on their outer sides, but the outer diameter being smaller than that of the threaded bore of the insulators in order 30 to leave room for cement between the thimble and insulator, the cement getting a firm hold on the thimble outer threads and on the insulator bore threads to rigidly secure it in place. Such insulators with the thimbles 35 therein are then screwed onto pins. It has, however, been found desirable in some instances to have the thimbles separable in the insulators and the object of my invention is to produce efficient separable thimble 40 structures.

Such separable thimble structures must have internal threads for accurately and snugly fitting the threads of pins and must have yielding and resilient outer threads for 45 accommodating the threading of the insulator bore which, as above stated, is not always accurate and true. The separable insulator structures of my invention meet with these requirements and on the accompanying 50 drawings such structures are shown. On these drawings—

55 Figure 1 is an elevational view of a pin with one form of improved separable thimble structure thereon together with an insulator in vertical diametral section,

Fig. 2 is a similar view of the upper end of the pin showing a modified separable thimble structure,

Fig. 3 is a top view of the thimble structure of Fig. 2,

Fig. 4 is a view of the upper end of a pin with a modified form of thimble structure and an insulator mounted thereon, the thimble structure and insulator being in vertical diametral section, and

Fig. 5 is an elevational view of the hood shown in Fig. 4.

Referring to Fig. 1, *p* represents a pin which is cylindrical at its upper end and provided with threads 10. The thimble structure shown comprises an inner thimble member 11 in the form of a cap whose cylindrical sides are pressed or rolled to form inner threading 12 and outer threading 13, this inner thimble structure being adapted 75 to intimately fit over the end of the pin with its inner threading 12 intimately engaging with the pin threading 10. The thimble structure has the outer thimble member 14 shown in the form of a wire 80 helix whose turns parallel the turns of the external threading 13 of the inner thimble member 11. The ends of the wire helix deflect into upper and lower slots 15 and 16 respectively cut into the inner thimble member, the slots permitting circumferential play 85 of the helix ends. The outer surface of the helix turns is adapted to receive the threaded bores of insulators, such as *I*, and when an insulator is applied the coöperation of 90 the helix with the inner thimble member is substantially the same as the coöperation of the helix with its support in my Patent No. 1,158,149, dated October 26, 1915. The helix is yieldable radially helically and its 95 turns are relatively bodily yieldable so that this outer thimble structure is very resilient and very readily accommodates itself to the ordinary irregularities in the threading of large sized insulators. The thimble structures can also be very readily inserted in or 100 withdrawn from the insulator. When the thimble structure is started into the insulator the upper end of the helix will be anchored against the outer edge of the slot 15 so that the remainder of the helix will be 105 free to contract helically to the extent of the lower slot 16 and the structure can therefore be very readily inserted into the insulator. When rotated in reverse direction to 110

effect withdrawal the lower end of the helix anchors against the outer edge of the slot 16 and the upper part of the helix can contract so that withdrawal can very easily be 5 accomplished. However, when the structure is fully within the insulator the spring of the helix will cause the turns to expand and clamp themselves securely against the threading of the insulator so that the structure 10 is securely locked in the insulator. The thimble structure can, of course, be first inserted into the insulator and the inner thimble member 11 then applied to the pin, or the thimble structure can be first applied 15 to the pin and the insulator then applied thereto.

In Figs. 2 and 3 a modified form of separable thimble structure is shown. The structure is in the form of a sheet metal cap 17 20 from whose sides longitudinal sections 18 are stamped and deflected outwardly. Before deflecting the sections the cap is rolled or pressed to provide internal threading 19 for intimately engaging the threading 10 of 25 the pin p , and then when the sections 18 are deflected they will have outer threading 20 for engaging with the threading of the insulator such as I. These tongues 18 deflected from the thimble structure cap thus 30 provide the resilient and yielding threaded seating for the threading of the insulator which may be more or less inaccurate and irregular. To strengthen the tongues their lower ends 21 may be deflected inwardly 35 and rounded at their lower ends to abut against and fit the pin threading 10. This sheet metal thimble structure can be readily inserted in or withdrawn from the insulator and when in place on the pin will afford a 40 secure yet resilient and yielding support for the insulator.

In Fig. 4 is shown another arrangement. Here the inner thimble structure is in the 45 form of a sheet metal cap 22 rolled to provide internal threading 23 for engaging the pin threading 10 and to provide external threading 24. A cap or hood 25 of pliable material, such as felt, is slipped over the sheet metal thimble 22 and is of a thickness

to snugly fill, under more or less compression, the space between the thimble 22 and the sides of the bore of the insulator I and by virtue of such compression to fit snugly against the threading 24 of the thimble and against the threading of the insulator bore. 50 It is evident, of course, that the sheet metal inner thimble member 22 can be omitted and the fabric cap applied directly over the threaded end of the pin. The hood gives the resilient and yielding seating for the 55 insulator and the thimble structure can be readily inserted in or withdrawn from the insulator.

I thus provide thimble structures which have inner threading for intimately and 60 snugly receiving the threaded end of a pin, and which have yielding outer threading to form resilient seating for insulators. I do not of course desire to be limited to the exact constructions and arrangements shown 65 as modifications are no doubt possible which would still come within the scope of the invention.

I claim as follows:

1. A detachable thimble structure comprising outer and inner members, the outer members being resilient and providing threading for receiving and clamping an insulator, the inner member forming a support for the outer members and being 70 threaded to fit an insulator pin.

2. A detachable thimble structure comprising an inner sheet metal cap member threaded to fit a supporting pin, and outer thread members yieldably supported on the 75 inner member and providing flexible threading for receiving and clamping an insulator.

3. A thimble structure comprising a sheet metal inner member threaded to fit a supporting pin, and an outer member in the 80 form of a wire helix supported on the inner member and providing flexible threading turns for receiving and clamping an insulator.

In witness whereof I hereunto subscribe 95 my name this 11th day of May, A. D., 1916.

CHARLES L. PEIRCE, JR.
